UNITED STATES PATENT OFFICE.

WILLIAM ANDERSON, OF ALTRINCHAM, AND THEODORE COVENTRY, OF SALFORD, ENGLAND.

GEAR-CUTTING MACHINE.

1,173,914.

Specification of Letters Patent. Patented Feb. 29, 1916.

Application filed March 7, 1914. Serial No. 823,254.

To all whom it may concern:

Be it known that we, WILLIAM ANDERSON, of 122 Hale road, Altrincham, in the county of Chester, England, and THEODORE COVENTRY, of Gresley Iron Works, Salford, in the county of Lancaster, England, subjects of the King of Great Britain and Ireland, have invented certain new and useful Improvements in Gear-Cutting Machines, of which

10 the following is a specification.

This invention relates to bevel wheel and like gear cutting machines of the type in which cutting tools, operating simultaneously on both sides of a tooth, are reciprocated on automatically adjusting or opening and closing guide arms in lines or paths always directed toward the apex of the pitch cone of the wheel. Such a machine is described in U. S. Patent No. 668772.

20 The object of our invention is to provide improved means for giving the required automatic opening and closing movements to the guide arms during the cutting operation so as to produce the correct involute or

25 other tooth form.

Our invention comprises the combination with the guide arms on which the cutting tools are reciprocated, of a dummy or former, having two surfaces of correct configuration, adapted to act upon said guide arms and to be traversed through an adjustable distance for the purpose hereinafter described.

30 Referring to the accompanying sheet of explanatory drawings:—Figure 1 is a front elevation and Fig. 2 an end elevation of part of a gear cutting machine having our invention applied thereto.

35 The same reference letters in the two views indicate the same parts.

In the application of our invention, we arrange the guide arms *a* in which the tool slides are traversed in the usual manner and pivot same about a point which is the apex 45 of the pitch cone of the bevel wheels being cut. Each of said arms has a slot *b* therein at its free end and a scale thereon, a bracket *c* being adapted to be fixed in the slot at a certain position indicated on the scale according to the pitch of the wheel being cut. Each bracket carries a roller *d* which bears upon a surface of involute configuration of a dummy or former *e*. Thus one roller bears upon the upper and one upon the lower side 50 of the former. The latter is mounted upon

a slide *f* which is traversed or reciprocated by means of the quadrant *g* connecting rod *h* and arm *i* which synchronize in their movements with the feed movements given to the blank during the cutting operations. The 60 arm *i* is actuated by means such as employed in the prior U. S. patent before referred to for actuating the similar arm *d*. The rate of movement and length of traverse of the slide *f* may be adjusted by varying the position of the end of the rod *h* in the arm *i* so that the rollers *d* may traverse a greater or less portion of the former surface during the cutting of a complete tooth and thus the angular distance through which the guide arms 70 *a* are moved be increased or diminished to suit the pitch of tooth and its corresponding curvature.

In operation, when for example a miter wheel of a certain tooth pitch is being cut, 75 the blank axis is set at an angle of 45 degrees to the path of the cutting tools. The brackets *c* in the guide arms *a* are adjusted in position to suit the tooth pitch, and the rollers *d* each contact with the former at a 80 point on the pitch line of the dummy. The parts being now locked in position, all movements of the blank saddle are communicated to the former.

To provide for the correct formation of 85 teeth in bevels of varying angles, the distance through which the former *e* is traversed during each stroke of the cutting tools is adjusted so that a more or less extended portion of the former is traversed by 90 the rollers contacting therewith. This arrangement provides for a variation in the total angular movement imparted to the guide arms *a* and therefore a variation in the starting and finishing positions of the 95 cutting tool, in the involute path.

We preferably provide a counter-weight *j* which tends to press the lower bracket *c* upward. The effective weight of the said counterweight is preferably twice the weight 100 of said bracket *c* and the roller *d* thereon. Thus when the two brackets are freed from the guide arms *a* for setting purposes, the pressure of the upper bracket upon the former will be exactly the same as the pressure 105 of the lower bracket thereon.

The guide arms *a* are balanced against one another by means of a steel band represented by *k* and when the machine is in operation the two brackets balance one another, 110

the pressure upon the two surfaces of the former *e* being that of the counterweight *j* only.

With our improved arrangement, bevel gears of any angle or ratio can be accurately cut, and likewise by varying the shape of the former, teeth having different pressure angles of any ratio can be generated. Further as the former is traversed by copying rollers *d*, the cutting operation may be accurately performed by round nosed tools having a radius proportional to the radius of the copying rollers and to the distance of the tool from the apex of the pitch cone when cutting.

Having now described our invention, what we claim as new, and desire to secure by Letters Patent is:—

1. In a gear cutting machine having reciprocating cutting tools operating simultaneously on both sides of a tooth, the combination with the guide arms carrying the said cutting tools, of a dummy or former having two opposite sides of correct configuration, means for traversing the said dummy or former through adjustable dis-

tances during the reciprocation of the cutting tools and means whereby the movements of the dummy or former impart the required opening and closing movements to the said guide arms, as set forth.

2. In a gear cutting machine having reciprocating cutting tools operating simultaneously on both sides of a tooth, the combination with the guide arms carrying the said cutting tools, of a dummy or former having its opposite sides of similar configuration, means for reciprocating the said dummy or former through adjustable distances, brackets adjustably mounted in the said guide arms, and rollers carried by the said brackets which contact with the respective sides of the dummy or former, as set forth.

In testimony whereof we have signed our names to this specification in the presence of two subscribing witnesses.

WILLIAM ANDERSON.
THEODORE COVENTRY.
